AUTOGRAPHIC REGISTER

William C. Pfeiffer and Frank E. Pfeiffer, Dayton,
Ohio, assignors to The Egry Register Company,
Dayton, Ohio, a corporation of Ohio

Application October 2, 1934, Serial No. 746,542

3. Claims. (Cl. 282—21)

This invention relates to improvements in autographic registers, and has for its object to use the same distance between creases for the width of the tickets and to vary the length of the tickets by varying the width of the sheet folded on the creases. By this arrangement it is possible to have a large number of lengths of sheets without changing the throw of the machine. By changing the size of the writing opening, or the size of the form, and writing on the sheet lengthwise rather than the usual crosswise position, this is accomplished.

It is understood that the variations in tickets take place primarily in length and that the variations in width are very much less. In other words, there are a large number of different tickets of similar widths. By selecting four standard widths of 8½", 6½", 5½" and 4¼" it is only necessary to have two types of machines; machines able to handle a 5½" width and the 8½" width.

This permits variation in lengths from 3" to 11", and variation in widths by either varying the machine throw or by multiplying the standard distance between the actuating pins. On one machine the spacing between pins is 2¾", which permits of using either a 5½" wide ticket or a 2¾" ticket. On the other type of machine the distance between pins is either 4¼" or 8½".

Another advantage of the invention is that the press can be set up for the printing of standard forms with a very small variation, so as to eliminate the make-ready and set-ups of the press. The only change that need be made in the machine is either to adjust a pair of guides or substitute a lid with a larger or a smaller opening over the writing table. By this arrangement there is a constant throw; that is, a constant width of form between creases and a variation of the length of the sheet, which becomes a transverse dimension of the sheet.

These and other advantages will appear from the following description taken in connection with the drawings.

The preferred form of the invention is shown in the accompanying drawings, of which Figure 1 is a top plan view.

Figure 2 is a section on the line 2—2 of Figure 1.

Figure 3 is a section on the line 3—3 of Figure 2.

The operating mechanism is inclosed within a substantially rectangular casing 1, which has at one end thereof a lid or cover 2 pivoted to one end of the casing by means of ears 3 and pivots 4.

This cover or lid has therein the usual writing opening 5. It also is provided at the end remote from its pivot with an arcuate part 5a, terminating in an end 6 engaged by means of a lid or cover 7 pivoted by means of ears 8 and a pivot 9 to the end of the casing remote from the pivots 4.

Beneath the opening 5 and within the casing is a table 10 pivotally supported at one end by means of ears 11 and pivots 12, while it is supported at its other end by means of studs 13 located on the sides of the casing. Near the pivoted end of the table is a transversely extending slot 14 adapted to be partly closed by means of an aligning plate 15 supported on the under side of the table by means of studs or supports 16. To this plate is attached one end of a bar 17, which has its other end 18 bent down to receive a bolt 19 supported adjustably thereon by means of nuts 20. This bolt has thereon a head 21, the purpose of which will be later described.

Attached to the bar 17 is a lug 22, which has attached thereto one end of a coil spring 23, the other end of which is attached to a post 24, supported on the table and extending through a slot in the bar for supporting and guiding the bar in its longitudinal movement for operating the aligning plate 15. For the purpose of supporting the bar 17 adjacent the lower face of the table the post 24 is provided with a washer 25 which engages the under-surface of the bar.

Within the arcuate part 5a of the cover 2 is a presser roller 26, supported at each end by means of a bar 27. Each bar 27 has in its upper end a hole to receive a bearing member of the roller. In each bar 27 are slots 28 to receive pins 29 located in the side of the casing for guiding the bar. The lower end of each bar is bent inwardly as at 30, just above a bracket 31 attached to the side of the casing.

Extending through the bent part 30 of the bracket 31 is a bolt 32. The head of this bolt rests upon the part 30 and has on its lower end a nut 34, which serves to compress a spring 33 located between the nut and the bracket. These springs act upon the bars 27 to hold the roller 26 in its lowermost position so that it will engage feed discs 37 located upon a feed shaft 35 suitably supported in bearings in the sides of the casing immediately beneath the presser roller. The ends of the shaft 35 extend through slots provided therefor in the bars 27 so that the bars may freely move up and down.

The center of the shaft 35 is provided with a sleeve 36, which has at each end thereof the disc 37. These discs cooperate with the presser roller 26.

in feeding the group of strips of paper across the writing table. Each disc has about one-third of its periphery cut away at 38 so that during one complete rotation of the disc the feeding operation takes place during about two-thirds of the operation. There is also attached to one end of the shaft 35 a cam member 39 adapted to operate through other instrumentalities the aligning plate 15.

Cooperating with the cam member for operating the aligning plate is an arm 40 pivoted at its lower end at 41 to one side of the casing. The part of the arm 40 remote from its pivot is enlarged to form a head-like structure 43, which has thereon a lip 42 for engagement with the head 21 of the bolt 19 for operating the bar 17 and the aligning plate 15. Intermediate its ends the arm 40 is provided with a slot 44 into which a pin 45, supported on the side of the casing, projects for limiting the movement of the arm.

At one end of the casing beneath the lid 2 is a stack 46 of folded strips of paper, arranged in superimposed relationship to form groups 47. These strips as they leave the stack 46 pass over a guide rod 48 supported by the sides of the casing immediately beneath the slot 14. These strips after passing over the guide rod 48 pass by one edge of the aligning plate and onto the table toward the presser roller 26. The rod 48 has a pair of strip-engaging collars 48a.

As the group is fed forwardly, because of the action of the presser roller and the feeding disc, the upper strip 49 passes out of the casing above the lid 7, while the other strips 50 pass into the other end of the casing, into a stack 51. In passing into this stack the strips 50 are guided by means of a loop 52. The strip 49 passes through a slot 53 provided therefor in the lid 2 adjacent the part 5a.

At one side of the casing is a carbon paper container 54, which has thereon a lid 55. The parts of the presser roller adjacent the feed discs are knurled, as indicated by the numeral 56. For the purpose of causing the presser roller to rotate with the feed shaft the feed shaft is provided with a gear 57, which meshes with a pinion 58 located on one end of the presser roller. The feed shaft is operated by means of a handle 59.

For the purpose of stopping the rotation of the feed shaft at the end of each rotation, a stop 60 is provided. This stop may be released for additional and other rotations of the feed shaft.

As shown in Figure 2, the strips of paper are gripped and aligned and held in tense and tight condition. Figure 2 shows the condition of the operating parts during the period of writing and at the beginning and at the end of each operation.

As soon as the handle is operated to advance the strips the lip 42 is brought out of engagement with the head 21 of the bolt 19 so that the aligning plate is withdrawn so that the strips of paper may readily pass through the slot 14. This feeding movement of the paper continues until the rotation is about two-thirds complete. During the remainder of the rotation the cam member 39 contacts with the arm 40 so that the lip 42 is brought into contact with the head 21 of the bolt 19, thereby forcing the aligning plate to substantially cover the slot 14 and grip the paper between the aligning plate and the table, at the part of the slot adjacent the pivots 12. This operation of the aligning plate causes the strips of paper to be aligned, and after the strips are aligned the feeding discs again engage the strips 75 so the strips of paper are tightened, and crimps

removed. The paper is again in the condition shown in Figure 2.

In this form of autographic register strips of varying widths may be used by replacing the cover by another cover having a writing opening 5 therein of less or greater width. For accommodating strips of paper of various widths the collars 48a may be adjusted along the rod 48.

It will be understood that it is desired to comprehend within this invention such modifications 10 as come within the scope of the claims and the invention.

Having thus fully described our invention, what we claim as new and desire to secure by Letters Patent, is:

1. In an autographic register, a casing, a table in the casing, said table having a slot through which a group of superimposed creased strips of paper pass onto the table, a flat plate adapted to slide on the underside of said table across the slot 20 and cooperate with the table at one side of the slot to engage the strips in the creases between an upper edge of said plate and the lower edge of said slot and align them, rotating members supported by the casing, means on the rotating members 25 to grip and move the strips across the table during the first part of a rotation thereof and to release the strips during the second part of said rotation, and means operated by one of said members to slide the plate across the slot near the end 30 of said second part of said rotation, said first-named means coming into operation at the end of the second part of the rotation, said last-named means comprising an arm pivoted at one end and a cam member operating on the other end of 35 the arm.

2. In an autographic register having a flat paper table with a transverse paper guiding slot therein, the combination with a casing and paper-feeding mechanism comprising a pair of rotatable 40 cylindrical devices mounted on a transverse shaft, of paper-aligning devices comprising a pivoted arm actuated by a cam mounted on said shaft, and an aligning device comprising a planar plate 45 slidably engaging the under surface of the table spring-actuated in one direction and by said arm in the other direction to wedge the paper sheets between the upper forward edge of said plate and the lower edge of said slot to align them by partially closing said slot; said feeding mechanism 50 having a portion of its periphery cut away, so that the feeding is suspended and the sheets of paper released when the aligning device is acting on the paper.

3. In an autographic register having a slotted 55 table therein, the combination with a casing, and paper-feeding devices comprising a rotatable roller and rotatable disks adapted to grip the several paper sheets and feed them, of a paper-aligning device comprising a pivoted arm actuated by the feeding mechanism, a sliding flat paper aligning plate under the slotted paper table and in engagement therewith actuated to grip the paper between the upper forward edge of said plate and a lower edge of said slot and pull the several sheets 60 to align them, a self-actuating device to move the plate in the opposite direction, and guide devices including the transverse slot in the table adapted to act on the edges of the paper sheets to guide them to their position on the writing table of the machine; the feeding disks being cut away in a portion of their periphery to stop the feeding action during the operation of the aligning devices.
